F-15-2.

Inventor

G. V. Hedstrom,

By *Alfred L. Johnson Jr.*
Attorney

UNITED STATES PATENT OFFICE.

GUSTAV VERNER HEDSTROM, OF KENOSHA, WISCONSIN.

CONTROL FOR VARIABLE RADIO TUNING UNITS.

Application filed February 5, 1925. Serial No. 7,188.

This invention relates to radio receiving sets, and more particularly to variable tuning units thereof.

The invention has for one of its objects the provision of novel and simple means through the medium of which all of the variable tuning units of a set may be simultaneously adjusted or rotated from a single or master control.

10 A further object of the invention is the provision of means of the character stated which shall be adapted to permit the tuning units to be simultaneously adjusted or rotated with the minimum of play or lost motion, 15 which shall be adapted to permit the tuning units to be adjusted or rotated through an arc greater than 180°, and which shall be adapted to permit the tuning units to be uniformly and smoothly adjusted or rotated. 20 With the above and other objects in view, the invention consists of the construction, combination and arrangement of parts hereinafter fully described and claimed, and illustrated in the accompanying drawing, 25 wherein:

Figure 1 is a top plan view of a fragmentary portion of a radio receiving set, illustrating the application of my invention to the tuning units thereof, and

30 Figure 2 is a detail view in side elevation of the invention.

Corresponding and like parts are referred to in the following description, and designated in the accompanying drawing, by similar reference characters.

In the drawing, 1 and 1^a designate the tuning units, and 2 the panel of a radio receiving set. The tuning units 1 and 1^a are of the variable type and are carried by a plate 3 which may be made of metal or dielectric material and which is secured to the panel 2 in spaced relation to the inner side thereof by screws 4 and spacing sleeves 5. Only one of the shafts 6 and 7 of the tuning units 1 and 1^a, respectively, extends outwardly beyond the panel 2, and mounted upon the outer end of this shaft, which is in the present instance shaft 6, is a master control preferably in the form of a knob 8.

45 In accordance with my invention, the shafts 6 and 7 are so connected that, when the master control 8 is turned, the tuning units 1 and 1^a are simultaneously turned to an equal degree. This connection is established by similar angle levers 9 and 10 secured respectively to the shafts 6 and 7, a link 11 se-

cured to the outer arm 9^a of the lever 9 and the inner arm 10^a of the lever 10, and a link 12 secured to the inner arm 9^b of the lever 9 and the outer arm 10^b of the lever 10. The 60 links 11 and 12 are provided with arms 11^a and 11^b and arms 12^a and 12^b, respectively, which are pivotally connected at their outer or free ends to the outer or free ends of the arms of the levers 9 and 10. The arms of 65 each link are arranged at a similar inclination with respect thereto, and the links are secured to the levers 9 and 10 with their arms extending in opposite directions. The angle levers 9 and 10 are provided with openings 9^c and 10^c, respectively, to permit them to be mounted on the shafts 6 and 7, and are fixed to the shafts by set screws 9^d and 10^d, respectively.

70 Although only a pair of variable tuning units are shown connected for simultaneous adjustment or rotation, it is to be understood that a greater number may be so connected, and this may be done by increasing the length of the links 11 and 12 and providing 75 them with additional arms.

75 From the foregoing description, taken in connection with the accompanying drawing, it will be apparent that I have provided a device through the medium of which the 80 variable tuning units of a radio receiving set may be simultaneously adjusted or turned through the medium a master control, and that the device is simple and easy of application.

90 While I have described the principle of operation of the device, together with what I now consider to be the best embodiment thereof, I desire to have it understood that the structure shown is merely illustrative and that such changes may be made therein as fall within the scope of the following claim.

95 What is claimed is:—

In combination, a number of tuning units including shafts, a lever connected to the shaft of each unit and having angularly related arms, a link having inclined arms pivoted to corresponding arms of the levers, and a second link having arms inclined oppositely to the arms of the first link and pivoted to 100 the other arms of the levers, the lever arms occupying a position at one side of the shafts and the links occupying a position at the opposite side of the shafts in one adjusted position of the tuning unit.

105 In testimony whereof I affix my signature.
GUSTAV VERNER HEDSTROM.
